UNITED STATES PATENT OFFICE.

WALTER G. MORRISON, OF WILLIMANTIC, CONNECTICUT; HUBER CLARK, ADMINISTRATOR OF SAID MORRISON, DECEASED, ASSIGNOR TO THE ATWOOD-MORRISON COMPANY, OF STONINGTON, CONNECTICUT, A CORPORATION OF NEW JERSEY.

SWIFT-BRACKET.

SPECIFICATION forming part of Letters Patent No. 729,084, dated May 26, 1903.

Application filed June 14, 1896. Serial No. 594,254. (No model.)

To all whom it may concern:

Be it known that I, WALTER G. MORRISON, a citizen of the United States, residing at Willimantic, in the county of Windham and State 5 of Connecticut, have invented certain new and useful Improvements in Swift-Brackets, of which the following is a full, clear, and exact description, whereby any one skilled in the art can make and use the same.

10 The object of my invention is to provide a bracket for supporting a swift for winding silk, cotton, or other threads or filaments. As commonly used the brackets supporting the swifts are rigid and not capable of adjustment, while the conditions of use require a vertical change of position of the swift in order to obtain the best results.

To this end my invention consists in the sectional bracket, the sectional clamp, and 20 means for securing the bracket to the rail of a winding-frame and in the combination of the several parts making up the device as a whole, as hereinafter described, and more particularly pointed out in the claims.

25 Referring to the drawings, Figure 1 is a top or plan view showing the bracket with a swift mounted in the sockets. Fig. 2 is a detail view in section through the rail of winding-frame and in side view of one of the arms of 30 the bracket and on enlarged scale. Fig. 3 is a detail top view of one of the arms on enlarged scale.

In the accompanying drawings the letter 35 a denotes the side portion or swift-supporting rail of a winding-frame, along which the swifts b are located. In the form of swift-supports commonly used the arms supporting the swifts are secured rigidly to the frame, and by my invention I have provided means 40 whereby the swifts are adjustably supported in place on the frame, thereby securing better results in the winding operations.

The letter c denotes a bracket having on 45 its under side a wedge-shaped recess c', fitting a wedge-shaped projection a' on the frame a, by means of which the bracket is securely fastened in place on the frame, as by means of a bolt d passing through a slot a'

in the frame, as shown in dotted lines in Fig. 3 of the drawings.

An ear c² is located on the bracket c, through which projects a clamp-bolt e, provided with a clamp-nut e'. The arm f bears on one end an ear f', having a flat surface on one side fitting a flat surface on the side of the ear c² 55 and with a shoulder f² overlying and fitting the outer circular surface thereof. The opposite end of the arm is provided with swift-supporting sockets f³, in which the trunnions b' on the swift are supported. The swift- 60 sockets f³ are preferably located on opposite sides of the arm, with a web f⁴ separating the sockets on opposite sides of the arm and preventing the ends of the trunnions from interfering with each other in their rotation. These 65 sockets may be arranged in the end of the arm in any desired number and in any desired position with reference to each other, the sockets shown in the drawings herein being arranged on a line diagonally to a line 70 drawn lengthwise centrally along the arm, so that the position of the swifts with relation to the distance from the frame may be varied at will.

The swift-supporting sockets are formed 75 with open sides looking upward, so that the swifts may be easily and quickly placed on or removed from the arms, two of the arms being used to support a single swift and the arrangement of the sockets on opposite sides 80 of the arms enabling each arm to support the ends of two adjacent swifts.

It is obvious that other means of supporting and clamping in position an arm adapted to support the ends of a plural number of 85 swifts may be employed and that the sockets in the ends of the arms may be differently arranged with reference to each other without the aid of anything more than mere mechanical skill and without departing from the main 90 feature of the invention.

I claim as my invention—

1. In combination in a winding-frame, a swift-supporting rail, a plural number of bases adapted to be secured to the rail, a swift- 95 arm pivoted to each base at or near the rail,

- each arm having on its outer end means for supporting the ends of two adjacent swifts, and means for locking each arm against pivotal movement.
5. 2. In combination with a winding-frame, a swift-supporting rail, a plural number of bases adapted to be secured to the rail and having means of adjustment lengthwise of the rail, a swift-supporting arm pivoted to each base at or near the rail, each arm having at its outer end means for supporting the ends of two adjacent swifts, and means for locking the arm against pivotal movement.
3. In combination in a winding-frame, a swift-supporting rail secured thereto and having beveled faces on its upper surface, a plural number of bases fitting the beveled faces of the rail, a swift-arm pivoted to each base at or near the rail each arm having at its outer end means for supporting the ends of two adjacent swifts, and means for holding the arm against pivotal movement.
4. In combination in a winding-frame, a swift-supporting rail, a series of two or more bases adjustably mounted upon the rail, a swift-supporting arm pivoted to each base at or near the rail, each arm having at its outer end recessed pockets on opposite sides to receive the swift-bearing of the ends of two adjacent swifts, and means for preventing pivotal movement of the swift-arm.
5. In combination in a winding-frame, a swift-supporting rail secured to the frame, a series of two or more brackets adjustably secured to the rail, a swift-arm pivoted to each bracket each arm having at its outer end, on each side thereof, two or more recesses for the support of the ends of two adjacent swifts, and means for preventing pivotal movement of the arm.

WALTER G. MORRISON.
